LOUIS H. VON OHLSEN, OF NEW HAVEN, CONNECTICUT, ASSIGNOR TO THE SAFETY CAR HEATING & LIGHTING COMPANY, A CORPORATION OF NEW JERSEY.

REGULATING APPARATUS.

Application filed May 28, 1926. Serial No. 112,332.

This invention relates to systems of electrical distribution, and more particularly to systems in which a relatively large number of devices, such as electric lamps, are operated 5 in series from a relatively high voltage source.

One of the objects of this invention is to provide a simple and thoroughly practical system of the above-mentioned character capable of dependable and reliable operation in 10 practical use. Another object is to provide a simple and thoroughly practical regulating means for safeguarding the serially connected lamps in such a system of distribution against over-voltage and hence against burning-out 15 of the lamps, either due to wide changes in the voltage of the source or due to changes in the total resistance of the serially connected lamps as one or more of the latter become burned out. Another object is to provide 20 regulating apparatus of the above-mentioned character which will be simple and inexpensive in construction, capable of embodiment in compact practical form, and well adapted to meet the widely varying conditions of hard 25 practical use. Other objects will be in part obvious or in part pointed out hereinafter.

The invention accordingly consists in the features of construction, combinations of elements, and arrangements of parts as will be 30 exemplified in the structure to be hereinafter described and the scope of the application of which will be indicated in the following claims.

In the accompanying drawing, in which are 35 shown several of various possible embodiments of certain of the electrical features of my invention,

Figure 1 is a diagrammatic representation of the circuit arrangements and of the apparatus embodying a preferred form of my invention;

Fig. 2 is a like diagrammatic representation illustrating a modification of certain features of my invention; and

Fig. 3 is a like diagrammatic representation illustrative of a modification in certain details of my invention and illustrative of the achievement of certain other advantages of my invention.

Similar reference characters refer to similar parts throughout the several views of the drawings.

As conductive to a clearer understanding of certain features of my invention, it may at

this point be noted that in certain systems of electrical distribution, such as in certain systems of illumination, for example, the source of current is of a voltage relatively high with respect to the voltage of the individual lamps which it is desired to employ; in such systems 60 it is usual to connect the individual lamps in series so that the total voltage available is commensurate with that of the summation of the operating voltages of the individual lamps. Such systems of illumination, however, largely employed in rapid transit vehicle service such as subways and the like, are characterized by a number of disadvantages and limitations which my invention aims to overcome. For example, the burning-out of 70 one lamp in such systems makes the entire series of lamps inoperative, and even though the lamp thus made inoperative may be short-circuited so as to complete the circuit, the remaining lamps are thereby made to operate at 75 an abnormally high voltage with the result that they are rapidly burned out.

A dominant aim of my invention is to provide a thoroughly practical system of illumination in which any desired number of lamps of appropriate potential may be serially arranged to be operated from a relatively high voltage source and wherein the burning-out 80 of one or more or any number of the lamps in a circuit may take place without endangering the remaining lamps; and a further aim of my invention is to achieve this object with 85 apparatus and devices of simple and inexpensive construction.

Referring now to the drawing, and more particularly to Fig. 1, there is shown at 10 a suitable source of current which may, for example, be of a potential in the neighborhood of from 450 to 700 volts or thereabouts. A plurality of lamps or translating devices 11 are connected in series, and though in the drawing only four of such devices are shown, it will be understood that any suitable or appropriate number may be thus arranged. Each device or lamp 11 is provided with a 100 device generally and diagrammatically indicated at 12, arranged so that when one of the lamps 11 burns out, the device 12, associated with that lamp, short-circuits the terminals of the burned-out lamp, thereby to 105 maintain the series circuit through the remaining lamps 11 intact. The device 12 may take any suitable or appropriate form, for

example, such as what is known as a "filament cutout", and need not be specifically illustrated or described.

The series of lamps 11 is connected by conductor 13 to one side of the source of current 10, whereas a conductor 14 leading from the other terminal of the source 10 completes the circuit through a current coil 15, a variable resistance 16, the latter preferably in the form of a pressure-responsive carbon pile, thence through any appropriate number of serially arranged fixed resistances, of which only two are shown in the drawings, namely, the resistances 17 and 17^a. Each of the fixed resistances is normally short-circuited by an appropriate switch; thus the resistance 17 is short-circuited by the switch 18 and the resistance 17^a is short-circuited by the switch 18^a.

20 The pressure on the carbon pile resistance 16 is variable by means of a bell-crank lever 19 pivoted as at 20, a spring 21 acting to tend to compress the carbon pile 16. Associated with the current coil 15 is a core 22 connected to an end of the bell-crank lever 19 so that any tendency of the current in the circuit, which, when the parts are in the position shown in Fig. 1, will be seen to include the coil 15, variable resistance 16, and the serially connected lamps 11, to increase beyond a value commensurate with the normal rating of the lamps 11 will cause a decrease in the pressure upon the carbon pile 16 with consequent increase in the resistance of the latter. The carbon pile regulator therefore will maintain substantial constancy of current in the series circuit, not merely throughout changes in the potential of the source 10, which potential may vary substantially, but also throughout changes in the total resistance of the serially connected lamps 11 throughout a predetermined range.

The carbon pile regulator is of relatively low capacity, in order to achieve greater nicety of regulation as well as to achieve greater efficiency; and assuming that one of the lamps 11 burns out, its terminals are at once short-circuited by its associated device 12, but the corresponding decrease in the total resistance of the series of remaining lamps 11 is at once compensated for by a commensurate increase in the resistance of the carbon pile 16, due to the action of the solenoid 15-22. As successive lamps 11 burn out, this action of maintaining substantial constancy of current through the remaining lamps by the carbon pile regulator 16 is repeated until the maximum ohmic value of the carbon pile 16 has been reached. Further burning out of lamps, therefore, would find the remaining operative lamps devoid of further protection against increase in current due to the range of action of the carbon pile resistance 16 having become exhausted. And it is at this point that one of

the plurality of fixed resistances 17-17^a, etc. is brought into action.

The switch 18 is held in short-circuiting position by a coil or magnet 23 connected by conductors 24 and 25 across the series of lamps 11; the switch 18^a is held in short-circuiting position by a coil or magnet 23^a also connected across the series of lamps 11. Magnet 23, however, is so constructed that it permits the switch 18 to open as soon as a reduction in voltage across the series of lamps 11 has taken place, which reduction will be commensurate with that due to the burning-out of enough lamps 11 to cause the carbon pile regulator 16 to reach substantially its maximum ohmic value. When such a reduction has taken place, switch 18 opens, and fixed resistance 17, the value of which is substantially equivalent to the maximum ohmic value of the carbon pile 16, becomes inserted in the series circuit. The consequent tendency to reduce the current in the circuit permits the spring 21 to bring the carbon pile 16 up to substantially its maximum compression so that the carbon pile regulator, under the control of the current coil 15, may commence its regulating action throughout its entire range of change in ohmic value.

As soon as the carbon pile 16 has again reached its maximum ohmic value due to the continued burning-out of lamps 11, and after one of the plurality of fixed resistances has been inserted in the circuit, a further and like reduction in voltage becomes effective to cause the magnet 23^a to open the switch 18^a and insert the next fixed resistance 17^a. The magnet 23^a, as will be understood from the foregoing, open-circuits the resistance 17^a at a voltage commensurate with that across the lamps 11 when the resistance 17 has already been inserted and the carbon pile 16 extended to its maximum ohmic value. The carbon pile 16 becomes again compressed under the action of the spring 21, and may repeat its regulating action throughout its range, as hereinbefore described, it being understood that as many fixed resistances and coacting relays or controlling switches therefor are provided as may be desired, each one being, as will now be clear, made operative at successive intervals of time corresponding to successive diminutions in the total resistance of the series of lamps 11 in increments corresponding to the maximum ohmic resistance of the carbon pile 16.

Thus the burning-out successively of any number of the lamps 11 is effectively prevented from causing the remaining operative lamps to be subjected to over-voltage, and it will be seen that the apparatus, even though the carbon pile regulator is of low capacity or low range, may be readily adapted to meet the widely varying conditions that may be met. As illustrative of the latter condition, it may be pointed out that my invention is

peculiarly of advantage where, for example, from eighteen to twenty 30-volt lamps are intended to be operated in series on a 550-volt circuit.

5 In Fig. 2, in which many of the parts illustrated in Fig. 1 are duplicated, the resistances 17 and 17^a are normally held short-circuited by the switches 18 and 18^a; the magnet controlling the opening of the switch 18 to bring 10 the fixed resistance 17 into the series circuit, however, comprises a current winding 26 connected to be responsive to the current flow in the series circuit; the winding 26 is preferably included directly in the series circuit. 15 The magnet controlling the switch 18^a includes preferably a voltage-responsive winding 27 connected by conductors 28 and 29 to be responsive to the potential drop across the resistance 17.

20 In operation, the switch 18 is opened by the magnet 26 when the carbon pile 16 can no longer, under the action of the solenoid 15—22, cause a further decrease in the current in the series circuit, that is, when the 25 ohmic value of the carbon pile 16 has reached its maximum. The fixed resistance 17 is thus brought into the circuit so that the carbon pile 16 may operate again throughout its complete range. As soon as the carbon pile has 30 again, however, reached its maximum value of ohmic resistance, the potential drop across the resistance 17 will have reached a corresponding predetermined value, and it is at this predetermined value that the magnet 27 35 opens the switch 18^a, thus to bring into the circuit the fixed resistance 17^a and to permit the carbon pile 16 to be operated again throughout its entire range. As is true of the 40 arrangement shown in Fig. 1, as many fixed resistances 17, 17^a, etc. with corresponding operating coils as shown in Fig. 2 may be employed.

In Fig. 3 I have illustrated a possible modified embodiment of certain features shown in the arrangement in Fig. 2. In the arrangement of Fig. 3, the switch 18 will be seen to be controlled by a current coil 26 operating as described in connection with Fig. 2, but instead of employing a fixed resistance 17 50 per se, the coil 30 of the switch 18^a (which controls the insertion of the resistance 17^a) is connected across the contacts of the switch 18 and has a resistance substantially equivalent to the maximum ohmic resistance of the 55 carbon pile 16.

In operation, therefore, a continued increase in current due to the inability of the carbon pile 16 to be further increased as to resistance, brings into action the current coil 60 26 so that switch 18 is opened; thus the coil 30 is brought serially into the circuit and with it also a resistance, embodied in the coil itself, equivalent substantially to the maximum ohmic value of the carbon pile 16. As 65 soon as the carbon pile has again reached its

maximum ohmic resistance, and due to its resultant inability to further bring about a decrease in the current as further lamps are burned out, for example, the resultant increase in the current through the coil 30 70 brings into action the switch 18^a to insert serially into the circuit a resistance diagrammatically shown in Fig. 3 as a fixed resistance 17^a but which may, as will be clear from the foregoing, include a coil of a successive 75 switch having a like resistance.

It will thus be seen that there has been provided in this invention a system and apparatus in which the several objects hereinbefore noted, as well as many practical advantages are successfully achieved. It will 80 be seen that the lamps are thoroughly safeguarded against changes in the potential of the source 10, and more particularly will it be seen that the series of lamps 11 are dependably safeguarded against changes that may be brought about due to one or more of the lamps becoming inoperative. The apparatus and system, it will be noted, is thus also well protected against abnormalities in 85 the electrical conditions which might arise due to either relatively slight or relatively large changes in the total resistance of the serially connected devices, such as the lamps 11, it being pointed out that such changes in 90 the total resistance of the serially connected devices are made effective not merely to bring about the regulating action of the carbon pile 95 regulator 16 but also the insertion into or the removal from the series circuit of the relatively fixed resistances 17, 17^a, etc. The controlling devices for the latter will be seen to be responsive directly to the changes in the 100 current in the circuit brought about by changes in the total resistance of the series of 105 lamps 11, whether the controlling coils or magnets for these switches be designated as current-responsive or voltage-responsive. Thus, for example, the windings 23 and 23^a 110 of Fig. 1, while in and of themselves of relatively high resistance, are connected to be responsive to the voltage drop across the series of lamps 11 and are therefore, in their action, made directly responsive to such changes in the total resistance as will effect a corresponding 115 I. R. drop through the lamps. Similarly, the current coil 26 of Fig. 2 will be seen to be directly responsive to current changes brought about by changes in total resistance of the series of lamps 11, while the coil 27 of 120 Fig. 2, shunted about the subsequently inserted resistance 17, will be seen to be likewise responsive to current changes due to changes in this total resistance. As for the coil 30 of Fig. 3, its action also will be seen to be dependent upon changes in the total 125 resistance of the series of devices 11. It will, of course, be understood that these various controlling coils, while thus made responsive to such changes in the circuit resistance 130

against which the system and apparatus is intended to be safeguarded, become active or effective only after the range of action of the carbon pile 16 has been exhausted.

5 It will furthermore be noted that the apparatus is thoroughly automatic in its action, and that the fixed resistances may be automatically cut out of the circuit in exactly the reverse manner from which they were inserted therein; that is, as inoperative lamps or devices 11 are made operative or replaced, thereby to change the total resistance of the series thereof, the controlling devices for the fixed resistances are correspondingly effective to cut out an appropriate number, or all, of the fixed resistances.

10 It will furthermore be seen that the apparatus is thoroughly practical in its nature, is of simple construction and reliable action, and may be embodied in relatively inexpensive and compact practical form. It will furthermore be seen that the system and apparatus of this invention is well adapted to meet the widely varying conditions of hard practical use.

15 As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

I claim as my invention:

20 1. In a system of the character described, in combination, a circuit having serially arranged therein a plurality of lamps, means associated with said lamps adapted to short-circuit the terminals thereof upon the lamp becoming inoperative, the total resistance of said lamps decreasing as lamps become inoperative, a variable resistance included in said circuit, a coil responsive to a function of the current flowing in said circuit for controlling said resistance and adapted therewith to maintain substantial constancy of current in said circuit as the total resistance of said lamps decreases, means responsive to a function of the current in said circuit for opening one of said switches when said variable resistance has been substantially extended throughout its range of variability, and means responsive to a function of the current in said first-mentioned circuit with one of said fixed resistances inserted therein for opening another of said switches substantially when said variable resistance has again been extended throughout its range of variability.

25 2. In a system of the character described, in combination, a circuit having serially arranged therein a plurality of lamps, means associated with said lamps adapted to short-circuit the terminals thereof upon the lamp becoming inoperative, the total resistance of said lamps decreasing as lamps become inoperative, a plurality of switches, one for each of said fixed resistances, and adapted to control the

variable resistance included in said circuit, a coil responsive to a function of the current flowing in said circuit for controlling said resistance and adapted therewith to maintain substantial constancy of current in said circuit as the total resistance of said lamps decreases and within the range of action of said variable resistance, a resistance serially arranged in said circuit and having an ohmic value substantially equivalent to the maximum ohmic value of said variable resistance, and a switch controlling the insertion of said second-mentioned resistance serially into said circuit and having a voltage-responsive coil connected across said serially arranged lamps and adapted to cause operation of said switch when a decrease in voltage across the lamps takes place commensurate with that caused by the maximum value of said variable resistance.

3. In a system of the character described, in combination, a circuit having serially arranged therein a plurality of lamps, means associated with said lamps adapted to short-circuit the terminals thereof upon the lamp becoming inoperative, the total resistance of said lamps decreasing as lamps become inoperative, a variable resistance included in said circuit, a coil responsive to a function of the current flowing in said circuit for controlling said resistance and adapted therewith to maintain substantial constancy of current in said circuit as the total resistance of said lamps decreases, means responsive to a function of the current in said circuit for opening one of said switches when said variable resistance has been substantially extended throughout its range of variability, and means responsive to a function of the current in said first-mentioned circuit with one of said fixed resistances inserted therein for opening another of said switches substantially when said variable resistance has again been extended throughout its range of variability.

4. In a system of the character described, in combination, a circuit having serially arranged therein a plurality of lamps, means associated with said lamps adapted to short-circuit the terminals thereof upon the lamp becoming inoperative, the total resistance of said lamps decreasing as lamps become inoperative, a variable resistance included in said circuit, a coil responsive to a function of the current flowing in said circuit for controlling said resistance and adapted therewith to maintain substantial constancy of current in said circuit as the total resistance of said lamps decreases and within the range of action of said variable resistance, a plurality of relatively fixed resistances each having an ohmic value substantially equal to the maximum ohmic value of said variable resistance, a plurality of switches, one for each of said fixed resistances, and adapted to control the

insertion serially of said fixed resistances in said circuit, and voltage coils, one for each of said switches, for operating the latter, each coil being responsive to a different voltage 5 exerted in said circuit.

5. In a system of the character described, in combination, a circuit having serially arranged therein a plurality of lamps, means associated with said lamps adapted to short-circuit the terminals thereof upon the lamp becoming inoperative, the total resistance of said lamps decreasing as lamps become inoperative, a variable resistance included in said circuit, a coil responsive to a function of the 10 current flowing in said circuit for controlling said resistance and adapted therewith to maintain substantial constancy of current in said circuit as the total resistance of said lamps decreases and within the range of action of said variable resistance, a plurality of 15 relatively fixed resistances each having an ohmic value substantially equal to the maximum ohmic value of said variable resistance, a plurality of switches, one for each of said 20 fixed resistances, and adapted to control the insertion serially of said fixed resistances in said circuit, and a plurality of voltage coils, one for each of said switches, connected in parallel across serially arranged lamps 25 and each adapted to operate its associated switch at a different voltage.

6. In a system of the character described, in combination, a circuit having serially arranged therein a plurality of lamps, means associated with said lamps adapted to short-circuit the terminals thereof upon the lamp becoming inoperative, the total resistance of said lamps decreasing as lamps become inoperative, a variable resistance included in said circuit, a coil responsive to a function of the 30 current flowing in said circuit for controlling said resistance and adapted therewith to maintain substantial constancy of current in said circuit as the total resistance of said lamps decreases and within the range of action of said variable resistance, a plurality of relatively fixed resistances each having an 35 ohmic value substantially equal to the maximum ohmic value of said variable resistance, a plurality of switches, one for each of said 40 fixed resistances, and adapted to control the insertion serially of said fixed resistances in said circuit, a plurality of coils, one for each of said switches, and means connecting 45 said coils to said circuit so that they become 50 operative at successive intervals to insert serially and successively said fixed resistances when the total resistance of said serially connected lamps diminishes in successive increments 55 equivalent to the maximum ohmic 60 value of said variable resistance.

7. In a system of the character described, in combination, a circuit having serially arranged therein a plurality of translating devices, each of which is provided with means 65 adapted to short-circuit the terminals of the device upon the latter becoming inoperative, the total resistance of said devices decreasing as successive devices become inoperative, means including a variable resistance for controlling a function of the current supplied to said translating devices, a relatively fixed resistance, means adapted to insert said relatively fixed resistance in circuit with said 70 variable resistance, and means operative upon said variable resistance having reached substantially its maximum range of operation for actuating said last-mentioned means.

8. In a system of the character described, in combination, a circuit having serially arranged therein a plurality of translating devices, each of which is provided with means 75 adapted to short-circuit the terminals of the device upon the latter becoming inoperative, the total resistance of said devices decreasing as successive devices become inoperative, means including a variable resistance for controlling a function of the current supplied to 80 said translating devices, a relatively fixed resistance having an ohmic value substantially 85 equivalent to the maximum ohmic value of said variable resistance, means for connecting said fixed resistance in series with said variable resistance, means for actuating said connecting means substantially only 90 when said variable resistance has reached its maximum ohmic value, a second relatively fixed resistance, and means operative when said variable resistance has again reached its maximum ohmic value for inserting said 95 second fixed resistance in series therewith.

9. In a system of the character described, in combination, a circuit having serially arranged therein a plurality of translating devices, the total resistance of which serially 100 arranged devices may vary in accordance with the number of devices included in the circuit, a regulator for maintaining substantially constant current in the said circuit throughout a predetermined range of change 105 in the total resistance of said devices, and means operative substantially when said predetermined range of change in total resistance has taken place for extending the range of said regulator, said last-mentioned means including a resistance adapted to be inserted in circuit with said serially arranged devices.

In testimony whereof, I have signed my name to this specification this 30th day of April, 1926.

LOUIS H. VON OHLSEN.
